UNITED STATES PATENT OFFICE

LA VERNE FRANKLIN WERTZ, OF BUFFALO, NEW YORK

AEROPLANE CONSTRUCTION

Application filed June 20, 1930. Serial No. 462,567.

My invention relates to improvements in aeroplane construction, and the object of my invention is to devise an improved upper wing supporting and actuating structure for the type of machine illustrated and described in my United States Letters Patent #1,748,262.

In this type of machine I furnish a rigid lower wing following general monoplane practice and also a superposed upper wing which can be raised or lowered by the pilot in flying, whereby the aeroplane can be converted from a monoplane into a biplane or vice-versa.

The object of the present invention is to provide a mechanism whereby the angle of incidence of the upper plane may be altered when the machine is being used as a biplane so that the changing air pressure due to the alteration in the angle of incidence will force the top plane downwardly into a position lying upon the upper face of the lower plane whereby the aeroplane is converted into a monoplane.

A further object of my invention is to provide a mechanism whereby the swinging movement of the struts which support the upper plane are synchronized, and a further object of my invention is to furnish a locking mechanism for retaining the upper wing in its adjusted position.

My invention consists of an aeroplane constructed and arranged all as hereinafter more particularly described and illustrated in the accompanying drawings, in which

Figure 1 is a front elevational view of my aeroplane showing it in biplane form.

Figure 2 is a similar view to Figure 1 showing my aeroplane in monoplane form.

Figure 3 is an enlarged vertical cross sectional view through the wings in biplane form.

Figure 4 is a similar view to Figure 3 showing the angle of incidence of the upper plane altered.

Figure 5 is a similar view to Figures 3 and 4 showing the wings together in monoplane form.

Figure 6 is a vertical longitudinal sectional

view of a fragmentary portion of the wings being taken through the line 6—6 Figure 4.

Figure 7 is a similar view taken through the line 7—7 Figure 5.

Figure 8 is also a similar view taken through the line 8—8 Figure 5.

Figure 9 is a perspective view of a fragmentary portion of the lower wing showing the strut receiving slots.

Figure 10 is an enlarged perspective view of a fragmentary portion of the lower end of one of the struts together with its connection to the lower plane.

Figure 11 is an enlarged cross sectional view through a portion of the upper end of one of the struts together with its connection to the upper plane, and

Figure 12 is a perspective view of one of the worm members contained within the upper plane and by means of which the swinging movement of the struts is synchronized.

Like characters of reference indicate corresponding parts in the different views in the drawings.

The aeroplane as illustrated in Figures 1 and 2 follows conventional practice in regard to the lower wing 1 fuselage 2, under-carriage 3 and tail 4, and apart altogether from my movable wing, can be flown as a monoplane.

The movable wing 5 is supported upon a plurality of struts which extend from the upper face of the lower wing and whereby such movable wing is supported in the conventional fashion when the machine is being flown as a biplane.

The forward struts 6 as illustrated in Figures 3 and 4 are of inverted V form and the rear struts 7 are of standard form, the forward struts being so formed for strength and rigidity. The lower ends of the struts 6 are formed with pivotal connections 8 secured to the lower plane whereby the struts are permitted an inward swinging movement as indicated in dotted lines in Figure 1. The lower ends of the struts 7 are also pivotally connected to the lower plane but as such rear struts are permitted a vertical movement when raised in addition to the swinging movement in being raised and lowered. I furnish the lower ends of such struts with the

connection illustrated in Figure 10. In this construction I furnish a pair of spaced apart members 9 which extend in alignment with the strut and are provided, in the vicinity of their lower ends, with a cross pin 10 which extends into a pair of slotted members 11 upon a bracket 12 which is secured interiorly of the lower plane.

The construction as illustrated in Figure 10 permits the rear strut 7 to have a vertical movement in respect to the lower plane 1 whereby the angle of incidence of the upper plane is altered as shown in Figures 3 and 4. For controlling the movement of the pins 10 within the slotted members 11 and consequently the vertical movements of the struts 7, I furnish in the lower plane 1, a plurality of inclined cam members 13 in the vicinity of the lower ends of the struts 7. These cam members 13 are mounted upon slidable rods 14, such rods being connected to a pair of integral swingably mounted arms 15 which are actuated through the medium of an actuating rod 16 which is under the control of the pilot. When the actuating rod 16, as illustrated in Figure 6 is moved downwardly the arms 15 have movement in a clockwise direction thus pulling the rods 14 and moving the inclined cams 13 inwardly for the purpose as shall be hereinafter explained.

In the vicinity of the lower face of the upper plane 5, I furnish two pair of worms 17 and 18, one pair extending across the forward portion of the wing and connected to their inner ends by a worm screw 19, and the other pair extending across the rear portion of the wings and connected by a worm screw 20. Extending between the worm screws 19 and 20 I furnish a rotatably mounted shaft 21 carrying upon its ends worm gears 22 and 23 which mesh with the worm screws 19 and 20. The worms are preferably formed of tubing having a spiral slot, and the slots in the tubes of each pair convolute in opposite directions as illustrated in Figure 6. The lower face of the upper plane 5 is formed with suitable slots 24 underneath the pairs of worms, and the upper ends of the struts are furnished with pivotally mounted members 25 which extend through the slots 24 and also through the spiral slots in the worm tubing.

The inner or the upper ends of the members 25 are formed with enlarged portions 26 which are contained within the tubes. When the upper wing 5 is being raised or lowered with the struts swinging upwardly or downwardly as the case may be, the worms all rotate under the motion of the members 25 along the slots in the respective worms.

As the pair of worms 17 and pair of worms 18 are connected together in their movement through the medium of the shaft 21 carrying the gears 22 and 23 which mesh with the worm screws 19 and 20, it will be seen that the struts

will have a synchronization of movement in their upward or downward swing.

For receiving the struts when they are in their lowermost position when the planes 1 and 5 are together I form the top of the plane 1 with a plurality of slots 27 into which the struts are received. These slots 27 are provided with swingably mounted doors 28 which are resiliently held and swing upwardly to close the slots 27 when the plane 5 is in the uppermost position thus providing a smooth face upon the lower plane.

For locking the planes together when the plane 5 is resting upon the plane 1 I furnish a pair of cam members 29 which are contained within such lower plane and project upwardly therefrom through slots 30. These locking members 29 are mounted upon sliding rods 31 which are connected to a pair of pivotally mounted arms 32 actuated through the medium of a rod 33 by the pilot. The lower face of the upper plane is furnished with a pair of angularly inclined pockets 34 into which the locking members 29 are received and in the vicinity of the entrance to the pockets 34 I furnish rollers 35 which engage the lower faces of the locking members 29 when they are about to enter the pockets.

When the wings are apart the locking members 29 are drawn towards one another through the medium of the rods 31 and the clockwise swingable movement of the arm 32 under the influence of the rod 33. When the upper plane is being lowered on to the lower plane in converting the machine from a biplane into a monoplane, the locking members 29 are moved outwardly under the influence of an anti-clockwise movement of the arms 32 and their lower faces engage and pass over the rollers 35 which are spaced away from the lower face of the upper plane in the vicinity of the pockets. As the planes approach one another the locking members 29 are moved to a further degree entering the pockets 30 until the planes are tightly together and the locking members 29 in the position illustrated in Figure 7.

The operation of my device is as follows:

As my machine is designed to combine the advantages of both a biplane and monoplane, that is the comparatively slow taking off and landing speed of the biplane and the fast flying speed of the monoplane, my machine will be in the biplane form as illustrated in Figure 1 when taking off. When the machine is in the air and has reached a sufficient altitude the pilot can then lower the top wing to convert the machine into a monoplane for faster flying. In order to do this the cam members 13 which extend between the members 9 upon the lower ends of the struts 7 and bear upon the pins 10 are moved outwardly through an anti-clockwise move-

ment of the arms 15 whereby the pins 10 are permitted to move upwardly in the slotted members 11 with a consequent upward movement of the struts 7 and a change in the angle of incidence of the upper plane 5.

This change in the angle of incidence changes the air suction from the top face of the plane 5 to its lower face thus tending to move the top plane down towards the lower plane. As the struts 6 and 7 are inclined as illustrated in Figure 1, they will swing inwardly under the downward pressure of the upper plane and as their upper ends are connected to the synchronizing worm mechanism, such movement of the struts will be in synchronization and the upper plane will remain parallel to the lower plane throughout its downward movement and the strain upon such upper plane will be taken up equally at all points of its span. As the upper plane approaches the lower plane, the locking members 29 are moved outwardly under anti-clockwise movement of the arms 32 whereby they enter the pockets 34 and lock the upper plane to the lower plane as hereinbefore described.

When it is desired to raise the upper plane the arms 32 are swung in a clockwise direction which will move the angular locking members 30 inwardly thus raising the front of the upper plane to a certain degree which will give it sufficient angle of incidence whereby the tendency of the upper plane will be to rise, and it will, therefore, move upwardly of its own accord away from the lower plane into the position illustrated in Figure 3. Whilst the upper plane is moving upwardly the arms 15 are swung in a clockwise direction drawing the cam members 13 inwardly whereby they engage the pins 10 in the slotted members 11 and move the rear struts downwardly so that when the upper plane reaches the upper extremity of its movement it has the correct flying angle of incidence.

From the foregoing description, it will be apparent that I have devised a very simple and effective upper plane supporting and operating mechanism whereby the various air pressures obtained through the alteration of the angle of incidence of such upper plane are utilized to move the upper plane into either the lowermost or uppermost position of its own accord, and although I have illustrated and described a particular embodiment of my invention it is to be understood that I can make such changes and alterations as I may, from time to time, deem necessary without departing from the spirit of the invention as set forth in the appended claims.

What I claim as my invention is:

1. In an aeroplane, the combination with the lower plane and an upper plane movable from a superposed position upon the upper face of the lower plane to a position in spaced

relation thereto, of means for altering the angle of incidence of the movable plane both when adjacent to the lower plane and when in the biplane position to alter the air pressures on such movable plane whereby such plane moves from one position to the other in lieu thereof. 70

2. In an aeroplane, the combination with the lower wing and an upper plane movable from a superposed position upon the upper 75 face of the lower plane to a position in spaced relation thereto, of a plurality of swingable struts pivotally mounted upon the lower plane and supporting the upper plane, and a synchronizing screw mechanism contained within the upper plane and to which the upper ends of the struts are connected. 80

3. In an aeroplane, the combination with the lower plane and an upper plane movable from a superposed position upon the upper 85 face of the lower plane to a position in spaced relation thereto, of a plurality of swingable struts pivotally mounted upon the lower plane and supporting the upper plane, and adjustable means forming a connection between the lower ends of the rear struts and the lower plane whereby the angle of incidence of the upper plane may be altered. 90

4. In an aeroplane, the combination with the lower plane and an upper plane movable from a superposed position upon the upper 95 face of the lower plane to a position in spaced relation thereto, of a plurality of swingable struts pivotally mounted upon the lower plane and supporting the upper plane, a synchronizing mechanism contained within the upper plane and to which the upper ends of the struts are connected, and adjustable means incorporated in the strut connection between the planes whereby the angle of incidence of the upper plane may be altered. 100

5. An aeroplane of the character described comprising a lower plane, an upper plane movable from a superposed position upon the lower plane to a position in spaced 110 relation thereto, a plurality of struts swingable from a substantially vertical position to a substantially horizontal position mounted upon the lower plane and supporting the upper plane, the upper face of the lower plane having slots formed therein for the reception of the struts when in the horizontal position, and means incorporated in the struts for altering the angle of incidence of the upper plane. 115

6. An aeroplane of the character described comprising a lower plane, an upper plane movable from a superposed position upon the lower plane to a position in spaced relation thereto, a plurality of struts swingable from a substantially vertical position to a substantially horizontal position mounted upon the lower plane and supporting the upper plane, slots formed in the lower face of the upper plane, worm members contained 120

within the upper plane adjacent to the slots, and connecting members extending from the upper ends of the struts through the slots and engaging the worm members.

- 5 7. An aeroplane of the character described comprising a lower plane, an upper plane movable from a superposed position upon the lower plane to a position in spaced relation thereto, a plurality of struts swingable from 10 a substantially vertical position to a substantially horizontal position mounted upon the lower plane and supporting the upper plane, slots formed in the lower face of the upper plane, worm members contained within the 15 upper plane adjacent to the slots, connecting members extending from the upper ends of the struts through the slots and engaging the worm members, the upper face of the lower plane having slots formed therein for the reception of the struts when in the horizontal position, and means incorporated in the struts for altering the angle of incidence of the upper plane.

- 20 8. An aeroplane of the character described comprising a lower plane, an upper plane movable from a superposed position upon the lower plane to a position in spaced relation thereto, a plurality of struts swingable from a substantially vertical position to a substantially horizontal position mounted upon the lower plane and supporting the upper plane, vertical slotted members extending from the lower plane, pins carried upon the lower ends of the rear struts projecting into the slots and movable therealong, and movable means carried upon the lower plane and engaging the pins to control their movement in the slots.

- 25 9. An aeroplane of the character described comprising a lower plane, an upper plane movable from a superposed position upon the lower plane to a position in spaced relation thereto, a plurality of struts swingable from a substantially vertical position to a substantially horizontal position mounted upon the lower plane and supporting the upper plane, vertical slotted members extending from the lower plane, pins carried upon the lower ends of the rear struts projecting into the slots and carried by the lower plane and engaging the pins to control their movement in the slots.

LA VERNE FRANKLIN WERTZ.
